UNITED STATES PATENT OFFICE.

HORACE M. CAPRON, OF WINNETKA, ILLINOIS, ASSIGNOR TO THE MARSH CAPRON MANUFACTURING COMPANY, OF CHICAGO, ILLINOIS, A CORPORATION OF ILLINOIS.

CONCRETE-MIXING APPARATUS.

1,209,668.

Specification of Letters Patent. Patented Dec. 26, 1916.

Application filed February 28, 1910. Serial No. 546,356.

To all whom it may concern:

Be it known that I, HORACE M. CAPRON, a citizen of the United States, residing at Winnetka, in the county of Cook and State 5 of Illinois, have invented certain new and useful Improvements in Concrete-Mixing Apparatus, of which the following is a specification.

My invention relates to a concrete mixing machine of the batch type, that is, to a form of mixing apparatus in which the materials are intermittently introduced into the mixing drum in measured amounts or batches and so mixed together and discharged therefrom, the product being in this manner kept substantially uniform in its character; and the invention has for its primary object to provide an apparatus of this type so constructed and capable of being so operated 10 that the work of handling the ingredients of the concrete at the street level may be continuous instead of intermittent as is the case with batch mixers which have been heretofore used. This work is usually done by 15 shovels and in the case of ordinary batch mixers the cement, crushed stone, etc., are shoveled by hand from piles of the material in the street, or other place where the machine is operating, into a charging hopper 20 which is intermittently hoisted and its contents dumped into the drum. While the charging hopper is being raised, discharged and lowered, the shovels must obviously interrupt their work and thus considerable 25 time is lost. There is another class of concrete mixing machines in which the materials going to make up the concrete are fed continuously into the mixing drum by means of bucket conveyors or similar continuously acting apparatus. In the case of 30 machines of this sort the work of the shovels can be uninterrupted, but this continuous method of charging is objectionable for reasons that are well understood and have led to this type of mixing machine falling into disuse.

My invention provides a machine in which the mixing apparatus is charged in batches, but which, at the same time, permits the

shovels to work substantially without interruption; thereby combining the advantages of the prior known systems while obviating their disadvantageous features.

The invention has for further objects such other new and improved constructions, arrangements and devices in concrete mixing machines as will be hereinafter described and claimed.

The invention is illustrated in certain preferred embodiments in the accompanying drawings, wherein—

Figure 1 is a side elevation of the apparatus, certain parts being shown in section; Fig. 2 a section taken on line 2—2 of Fig. 1; Figs. 3 and 4, details in elevation of the carrier, showing the same in different positions; Fig. 5 a sectional view on line 5—5 of Fig. 1, looking in the direction of the arrows; Fig. 6 a fragmentary view illustrating a modification; and Fig. 7 an end elevation of the form of apparatus shown in Fig. 7.

Like characters of reference indicate like parts in the several figures of the drawings.

Referring first to Figs. 1 to 5 inclusive, A represents a truck or carriage, of any preferred construction, supported on the pairs of wheels 10 and 11. The mixing device may be a batch mixer of any desired construction. I have shown a mixer of a usual type comprising a drum B supported on the rollers 12 and driven from a shaft 13 provided with the pinions 14 which mesh with the racks 15 on the drum. C is a discharge chute by which the mixed concrete is discharged from the drum, and D is a charging hopper. Preferably a slide gate or other valve or controlling device is provided for shutting off or controlling the feed of the material from the feed hopper to the drum. For example, a gate 16 may be slidably mounted in the hopper D in such manner as to close its feed opening 17 (Fig. 5). In the arrangement shown the movements of the gate 16 are controlled by a lever 18 rigidly secured to a rock shaft 19, the rock shaft carrying on its other end the short arm or lever 20, links 21 and 22 connecting

levers 18 and 20 respectively, with the gate 16.

I have shown and described a suitable form of mixing device but it will be understood that my invention is not limited to any particular construction of mixer. The mixer is charged by means of a carrier E which in turn is adapted to be filled from a bin F, which latter is placed near the ground and is intended to be filled, by hand labor or otherwise, from piles of material on the ground or elsewhere. After the carrier has received its load it is drawn up to a position above the feed hopper D over a track G and is then dumped, preferably by means which is automatic, into a feed hopper. The carrier E consists preferably of a car provided with the flanged rear wheels 23 and the flat wheels 24 arranged in advance of the flanged wheels 23. This construction is in conformity with the preferred construction of the track G, which, as shown, consists of a pair of angle irons, the horizontal flanges of which 25 support the wheels 24, while the vertical flanges 26 carry the flanged wheels 23.

Preferably, the lower portion II of the track is made separate from the upper portion G, being removably secured thereto, for example, by the splices 27. The bin F is mounted above this removable track portion II upon the supports 28. The bin may be of any desired construction. I have shown it as provided with the dumping bottom sections 29 and 30 which are hinged to the bin and are held in their closed position by means of the latches 31. The bin may have therein the deflector 32. Preferably, the track section H is supported on wheels 33.

The carrier or car E is provided with a bail 34 pivoted to the carrier back of its center and to this bail is secured the end of a cable 35 or other flexible connecting device, which cable runs over sheaves 36, 37 and 38, supported on a framework 39 and then over a drum or windlass 40.

Movement may be imparted to the various devices of my apparatus by driving means of any desired sort. I have shown, for purposes of illustration, an electric motor J, on the shaft 41 of which is loosely mounted the winding drum 40 adapted to be coupled to the shaft by the clutch 42 of any usual construction. The same motor may be employed for rotating the mixer B and to this end a clutch 43 is provided for coupling shaft 13 to the motor shaft 41. Ordinarily, in this form of apparatus, means is provided for moving the supporting truck which carries the apparatus. To this end, I provide the axle 44 of the truck with the sprocket wheel 45, which is connected by a chain 46 with the sprocket 47

on a counter-shaft 48 carrying a bevel gear 49, which is meshed with a bevel gear 50 adapted to be coupled with the motor shaft 41 by the clutch 51.

The carrier E may be dumped or otherwise discharged into the feed hopper D in any preferred manner. I have shown the flanges 25 of the angle iron tracks G cut away from the vertical flanges 26 and bent down into substantially horizontal position, as shown at 52. These track portions 52 may be supported on brackets 53 on the cross pieces 54, extending from the tracks G to the uprights of frame 39. The extremities of the track portions are curved up at 56 to form stops for the front wheels 24 of the carrier. As a result of this arrangement the carrier, when it reaches the upper end of the track, is tilted first into the position shown in Fig. 3 and afterward into that shown in Fig. 4. The front of the carrier is provided with a hinged door 57 which is normally held closed by a latch 58 pivoted to the carrier, the latch having a tooth 59 which engages a pin 60 on the door. If desired, the arrangement may be repeated on the other side of the door. The track portions 52 are preferably formed with offsets 61, so positioned that the wheels 24 pass over the same just as the latch or latches 58 come into contact with the stop 62, secured to the feed hopper D. The drop of the forward end of the car which results brings the latch 58 sharply into contact with the stop 62 and the load in the carrier pushing against door 57 opens the same, allowing the load in the carrier to be discharged into the feed hopper. Preferably the hopper is provided with a rest 63 for the end of the car. The dumping action is such as to discharge the material with some force from the carrier, insuring complete discharge.

In Figs. 6 and 7 I have shown a modified form of construction which relates merely to the supplementary truck, as it may be called, which carries the bin, indicated in this figure by F'. The supplementary truck in this case consists of a frame 64 secured to the frame of truck A' by the splice plates 65 and supported on wheels 66 which are mounted on an upright frame 67 in guides 68 on the truck frame 64. A screw 69, provided with a hand wheel 70, extends through the cross piece 71 of frame 64 and into a stationary nut 72 on the cross piece 73 of frame 67. Continuous with the tracks G' on the truck A' are track sections 74 which are pivoted to the tracks G' by the pivoted splice plates 75. The track sections 74 at their ends are formed with the slots 76 which receive the axle 77 which is secured to frame 67. The purpose of this arrangement is to level the track sections

74 in case the apparatus is standing on uneven ground.

As some modifications in the device and arrangement shown and described will readily suggest themselves to those skilled in this art, I do not limit myself to the exact constructions, arrangements, proportions and design of parts shown, except as these particulars are made limitations on the 10 claim hereof.

The operation of the apparatus above described is as follows: Assuming that the materials to be mixed, crushed stone, sand, cement and the like, are in piles on the 15 ground near the bin F (referring now to the apparatus particularly shown in the first five figures), these materials will be shoveled or otherwise deposited in the bin, the folding bottom sections 29 and 30 of which 20 are, of course, closed. When there is enough material in the bin to fill or approximately fill the carrier, the latches 31 will be released so that the material is dumped into the carrier. Clutch 42 will now be operated 25 to couple the windless or winding drum 40 with the motor shaft, and as a result, the carrier will be pulled up on track G and its contents dumped into the feed hopper D in the manner above described. In the arrangement shown the back of the carrier pushes against the folding bottom sections 29 and 30 of bin F and closes the same, the latches 31 being arranged so as to act by gravity. As soon as the bottom of bin F is 30 closed the shovels may begin filling the same again. With a proper force of shovels, the bin may be completely filled by the time car E has been returned to its position under the bin. To return the carrier the 35 clutch 42 is operated to uncouple the winding drum 40. The latter is shown as provided with an ordinary form of band brake 78 and this may be used to control the unwinding of cable 35 when the carrier is lowered. When the material is dumped into feed hopper D, its slide gate 16 is preferably 40 closed. To admit the charge into the mixer, which has been set in rotation by means of clutch 43, the operator presses down on lever 45 18 which throws up the feed gate 16. The feed gate may then be closed in readiness for another charge from carrier E. The same operator may also take care of the discharge when the mixing has proceeded sufficiently far. If the discharge chute C is 50 of the familiar tilting sort, which projects into the interior of the drum B, when it is in the position shown in Fig. 1, it will discharge the material from the drum. To 55 stop the discharge its inner end is tilted downward. This may be done by means of the lever 79 which is connected with the chute C by a link or links 80; the lever being held at any desired position by means

of the notched quadrant 81, engaged by the 60 tooth carrying rod 82 on the lever.

It will be seen that by this arrangement of parts the mixing can be carried on continuously and without any loss of time. The shovels may work almost uninterruptedly. 70 The bin may be filled often enough so that there is always a charge for the mixer ready whenever it may be proper to introduce new material. The whole apparatus is mounted on wheels and by coupling the apparatus 75 which drives wheels 14 with the motor shaft, by means of the clutch 51, the apparatus may be moved when desired. For example, it may be worked toward the piles of material on the ground as the latter are used up 80 and replaced by the new material brought in by wagons or the like.

Preferably the filling bin F has the same capacity as the carrier E, the hopper D and the mixer. The handling of the material 85 may, by the arrangement of parts shown, be carried out in batches of measured quantity, and this may be done by operations which proceed simultaneously and by apparatus which is simple in its character and inexpensive to construct and operate. While one batch is being mixed in the mixer, another batch is being transported in the carrier E from the filling bin to the charging hopper, and at the same time the shovels on the 90 street are filling up the filling bin F which measures the batch which is next in order. By the time the batch in the mixer is mixed and discharged the carrier will have dumped its load into the charging hopper and will 95 be on its way back to its position under the filling bin in readiness to receive the next batch. By operation of the gate 16 the batch in the hopper D is introduced into the mixer which will occur before the arrival of 100 the next batch in the carrier E. The apparatus thus constructed obviates the necessity for a separate measuring device.

When desired, the mixing apparatus proper on the main truck may be used without the filling bin, the supplementary truck in this case being detached from the main truck. It may be convenient to make this detachment also in moving the apparatus 110 from one job to another.

When the modified apparatus of Fig. 6 is used, the track on the supplementary truck may be leveled, in case the apparatus is working on uneven ground, by means of the screw 67 and the associated parts, as above 115 described.

It will be understood that any sort of motor or driving means may be employed for actuating the various moving parts of the apparatus. I have shown an electric motor 120 simply for convenience of illustration.

I claim:

In concrete mixing apparatus, the combi-

4
nation with a main truck, of a receptacle on
said truck, a supplementary truck, a bin on
the latter truck, said trucks being remov-
ably secured together, tracks on said trucks
5 which aline, a carrier adapted to be moved
back and forth on said tracks and to be
charged from the bin and to discharge into
said receptacle, the tracks on the two trucks

being pivoted together, and means for ad-
justing the level of the track on the supple- 10
mentary truck.

HORACE M. CAPRON.
